United States Patent Office

Des. 214,328
Patented June 3, 1969

214,328

TOY CAMERA

Ralph W. Crawford, East Aurora, N.Y., assignor to
Fisher-Price Toys, Inc., East Aurora, N.Y., a cor-
poration of New York

Filed Mar. 6, 1967, Ser. No. 6,062

Term of patent 14 years

Int. Cl. D21—02; D16—01

U.S. Cl. D34—15

FIG. 4

FIG. 5

FIG. 1 is a front perspective view of a toy camera showing my new design with the dotted line portion showing a conventional wrist strap;

FIG. 2 is a side elevation thereof as viewed from the right in FIG. 1;

FIG. 3 is a rear elevation thereof;

FIG. 4 is a top plan view thereof, and

FIG. 5 is a side elevation thereof viewed from the left in FIG. 1.

I claim:

The ornamental design for a toy camera, substantially as shown and described.
